DESCRIPTION

FIG. 1 shows a perspective view of a first embodiment of a design for an integrated tabbed note and clip kit.

FIG. 2 shows a top view of the first embodiment.

FIG. 3 shows a front view of the first embodiment.

FIG. 4 shows a right-side view of the first embodiment. A left-side view of this embodiment is a mirror image of this figure.

FIG. 5 shows a back view of the first embodiment.

FIG. 6 shows a bottom view of the first embodiment.

FIG. 7 shows a perspective view of a second embodiment of a design for an integrated tabbed note and clip kit.

FIG. 8 shows a top view of the second embodiment.

FIG. 9 shows a front view of the second embodiment.

FIG. 10 shows a right-side view of the second embodiment. A left-side view of this embodiment is a mirror image of this figure.

FIG. 11 shows a back view of the second embodiment.

FIG. 12 shows a bottom view of the second embodiment.

FIG. 13 shows a perspective view of a third embodiment of a design for an integrated tabbed note and clip kit.

FIG. 14 shows a top view of the third embodiment.

FIG. 15 shows a front view of the third embodiment.

FIG. 16 shows a right-side view of the third embodiment. A left-side view of this embodiment is a mirror image of this figure.

FIG. 17 shows a back view of the third embodiment.

FIG. 18 shows a bottom view of the third embodiment.

FIG. 19 shows a perspective view of a fourth embodiment of a design for an integrated tabbed note and clip kit.

FIG. 20 shows a top view of the fourth embodiment.

FIG. 21 shows a front view of the fourth embodiment.

FIG. 22 shows a right-side view of the fourth embodiment. A left-side view of this embodiment is a mirror image of this figure.

FIG. 23 shows a back view of the fourth embodiment.

FIG. 24 shows a bottom view of the fourth embodiment.

FIG. 25 shows a perspective view of a fifth embodiment of a design for an integrated tabbed note and clip kit.

FIG. 26 shows a top view of the fifth embodiment.

FIG. 27 shows a front view of the fifth embodiment.

FIG. 28 shows a right-side view of the fifth embodiment. A left-side view of this embodiment is a mirror image of this figure.

FIG. 29 shows a back view of the fifth embodiment.

FIG. 30 shows a bottom view of the fifth embodiment.

FIG. 31 shows a perspective view of a sixth embodiment of a design for an integrated tabbed note and clip kit.

FIG. 32 shows a top view of the sixth embodiment.

FIG. 33 shows a front view of the sixth embodiment.

FIG. 34 shows a right-side view of the sixth embodiment. A left-side view of this embodiment is a mirror image of this figure.

FIG. 35 shows a back view of the sixth embodiment.

FIG. 36 shows a bottom view of the sixth embodiment.

FIG. 37 shows a perspective view of a seventh embodiment of a design for an integrated tabbed note and clip kit.

FIG. 38 shows a top view of the seventh embodiment.

FIG. 39 shows a front view of the seventh embodiment.

FIG. 40 shows a right-side view of the seventh embodiment. A left-side view of this embodiment is a mirror image of this figure.

FIG. 41 shows a back view of the seventh embodiment.

FIG. 42 shows a bottom view of the seventh embodiment.

FIG. 43 shows a perspective view of an eighth embodiment of a design for an integrated tabbed note and clip kit.

FIG. 44 shows a top view of the eighth embodiment.

FIG. 45 shows a front view of the eighth embodiment.

FIG. 46 shows a right-side view of the eighth embodiment. A left-side view of this embodiment is a mirror image of this figure.

FIG. 47 shows a back view of the eighth embodiment.

FIG. 48 shows a bottom view of the eighth embodiment.

FIG. 49 shows a perspective view of a ninth embodiment of a design for an integrated tabbed note and clip kit.

FIG. 50 shows a top view of the ninth embodiment.

FIG. 51 shows a front view of the ninth embodiment.

FIG. 52 shows a right-side view of the ninth embodiment. A left-side view of this embodiment is a mirror image of this figure.

FIG. 53 shows a back view of the ninth embodiment.

FIG. 54 shows a bottom view of the ninth embodiment.

FIG. 55 shows a perspective view of a tenth embodiment of a design for an integrated tabbed note and clip kit.

FIG. 56 shows a top view of the tenth embodiment.

FIG. 57 shows a front view of the tenth embodiment.

FIG. 58 shows a right-side view of the tenth embodiment. A left-side view of this embodiment is a mirror image of this figure.

FIG. 59 shows a back view of the tenth embodiment.

FIG. 60 shows a bottom view of the tenth embodiment.

FIG. 61 shows a perspective view of an eleventh embodiment of a design for an integrated tabbed note and clip kit.

FIG. 62 shows a top view of the eleventh embodiment.

FIG. 63 shows a front view of the eleventh embodiment.

FIG. 64 shows a right-side view of the eleventh embodiment. A left-side view of this embodiment is a mirror image of this figure.

FIG. 65 shows a back view of the eleventh embodiment.

FIG. 66 shows a bottom view of the eleventh embodiment.

FIG. 67 shows a perspective view of a twelfth embodiment of a design for an integrated tabbed note and clip kit.

FIG. 68 shows a top view of the twelfth embodiment.

FIG. 69 shows a front view of the twelfth embodiment.

FIG. 70 shows a right-side view of the twelfth embodiment. A left-side view of this embodiment is a mirror image of this figure.

FIG. 71 shows a back view of the twelfth embodiment.

FIG. 72 shows a bottom view of the twelfth embodiment.

FIG. 73 shows a perspective view of a thirteenth embodiment of a design for an integrated tabbed note and clip kit.

FIG. 74 shows a top view of the thirteenth embodiment.

FIG. 75 shows a front view of the thirteenth embodiment.

FIG. 76 shows a right-side view of the thirteenth embodiment. A left-side view of this embodiment is a mirror image of this figure.

FIG. 77 shows a back view of the thirteenth embodiment.

FIG. 78 shows a bottom view of the thirteenth embodiment.

FIG. 79 shows a perspective view of a fourteenth embodiment of a design for an integrated tabbed note and clip kit.

FIG. 80 shows a top view of the fourteenth embodiment.

FIG. 81 shows a front view of the fourteenth embodiment.

FIG. 82 shows a right-side view of the fourteenth embodiment. A left-side view of this embodiment is a mirror image of this figure.

FIG. 83 shows a back view of the fourteenth embodiment.

FIG. 84 shows a bottom view of the fourteenth embodiment.

FIG. 85 shows a perspective view of a fifteenth embodiment of a design for an integrated tabbed note and clip kit.

FIG. 86 shows a top view of the fifteenth embodiment.

FIG. 87 shows a front view of the fifteenth embodiment.

FIG. 88 shows a right-side view of the fifteenth embodiment. A left-side view of this embodiment is a mirror image of this figure.

FIG. 89 shows a back view of the fifteenth embodiment.

FIG. 90 shows a bottom view of the fifteenth embodiment.

FIG. 91 shows a perspective view of a sixteenth embodiment of a design for an integrated tabbed note and clip kit.

FIG. 92 shows a top view of the sixteenth embodiment.

FIG. 93 shows a front view of the sixteenth embodiment.

FIG. 94 shows a right-side view of the sixteenth embodiment. A left-side view of this embodiment is a mirror image of this figure.

FIG. 95 shows a back view of the sixteenth embodiment.

FIG. 96 shows a bottom view of the sixteenth embodiment.

FIG. 97 shows a perspective view of a seventeenth embodiment of a design for an integrated tabbed note and clip kit.

FIG. 98 shows a top view of the seventeenth embodiment.

FIG. 99 shows a front view of the seventeenth embodiment.

FIG. 100 shows a right-side view of the seventeenth embodiment. A left-side view of this embodiment is a mirror image of this figure.

FIG. 101 shows a back view of the seventeenth embodiment.

FIG. 102 shows a bottom view of the seventeenth embodiment.

FIG. 103 shows a perspective view of an eighteenth embodiment of a design for an integrated tabbed note and clip kit.

FIG. 104 shows a top view of the eighteenth embodiment.

FIG. 105 shows a front view of the eighteenth embodiment.

FIG. 106 shows a right-side view of the eighteenth embodiment. A left-side view of this embodiment is a mirror image of this figure.

FIG. 107 shows a back view of the eighteenth embodiment.

FIG. 108 shows a bottom view of the eighteenth embodiment.

FIG. 109 shows a perspective view of a nineteenth embodiment of a design for an integrated tabbed note and clip kit.

FIG. 110 shows a top view of the nineteenth embodiment.

FIG. 111 shows a front view of the nineteenth embodiment.

FIG. 112 shows a right-side view of the nineteenth embodiment. A left-side view of this embodiment is a mirror image of this figure.

FIG. 113 shows a back view of the nineteenth embodiment.

FIG. 114 shows a bottom view of the nineteenth embodiment.

FIG. 115 shows a perspective view of a twentieth embodiment of a design for an integrated tabbed note and clip kit.

FIG. 116 shows a top view of the twentieth embodiment.

FIG. 117 shows a front view of the twentieth embodiment.

FIG. 118 shows a right-side view of the twentieth embodiment. A left-side view of this embodiment is a mirror image of this figure.

FIG. 119 shows a back view of the twentieth embodiment. FIG. 120 shows a bottom view of the twentieth embodiment. FIG. 121 shows a perspective view of a twenty-first embodiment of a design for an integrated tabbed note and clip kit. FIG. 122 shows a top view of the twenty-first embodiment. FIG. 123 shows a front view of the twenty-first embodiment. FIG. 124 shows a right-side view of the twenty-first embodiment. A left-side view of this embodiment is a mirror image of this figure. FIG. 125 shows a back view of the twenty-first embodiment. FIG. 126 shows a bottom view of the twenty-first embodiment. FIG. 127 shows a perspective view of a twenty-second embodiment of a design for an integrated tabbed note and clip kit. FIG. 128 shows a top view of the twenty-second embodiment. FIG. 129 shows a front view of the twenty-second embodiment. FIG. 130 shows a right-side view of the twenty-second embodiment. A left-side view of this embodiment is a mirror image of this figure. FIG. 131 shows a back view of the twenty-second embodiment. FIG. 132 shows a bottom view of the twenty-second embodiment.

FIG. 133 shows a perspective view of a twenty-third embodiment of a design for an integrated tabbed note and clip kit. FIG. 134 shows a top view of the twenty-third embodiment. FIG. 135 shows a front view of the twenty-third embodiment. FIG. 136 shows a right-side view of the twenty-third embodiment. A left-side view of this embodiment is a mirror image of this figure. FIG. 137 shows a back view of the twenty-third embodiment. FIG. 138 shows a bottom view of the twenty-third embodiment. FIG. 139 shows a perspective view of a twenty-fourth embodiment of a design for an integrated tabbed note and clip kit. FIG. 140 shows a top view of the twenty-fourth embodiment. FIG. 141 shows a front view of the twenty-fourth embodiment. FIG. 142 shows a right-side view of the twenty-fourth embodiment. A left-side view of this embodiment is a mirror image of this figure.
